UNITED STATES PATENT OFFICE

146,725

DESIGN FOR A HOLDER FOR BEER FOAM SCRAPERS OR SIMILAR ARTICLE

Val A. Schmitz, Manhasset, N. Y., assignor to The F. & M. Schaefer Brewing Co., Brooklyn, N. Y., a corporation of New York

Application November 28, 1945, Serial No. 124,135

Term of patent 14 years

(Cl. D2—3)

To all whom it may concern:

Be it known that I, Val A. Schmitz, a citizen of the United States and a resident of Manhasset, Nassau County, New York, have invented a new, original, and ornamental Design for a Holder for Beer Foam Scrapers or Similar Article, of which the following is a specification, reference being had to the accompanying drawings, forming a part thereof.

Fig. 1 is a top plan view of a holder for beer foam scrapers or similar articles, showing my new design;

Fig. 2 is a front elevational view thereof;

Fig. 3 is a sectional view thereof taken on section line 3—3 of Fig. 2; and

Fig. 4 is a rear elevational view thereof.

I claim:

The ornamental design for a holder for beer foam scrapers or similar article, as shown.

VAL A. SCHMITZ.
